ERNEST S. ROE, OF PLYMOUTH, MICHIGAN, ASSIGNOR TO KING MANUFACTURING COMPANY, OF PLYMOUTH, MICHIGAN, A CORPORATION OF MICHIGAN

AIR RIFLE

Application filed November 21, 1929. Serial No. 408,709.

This invention relates to air rifles, wherein a power spring and compressed air are utilized for expelling the projectile.

One of the objects of this invention is the provision of a simple, compact and efficient air rifle composed of comparatively few parts and that can be inexpensively manufactured and assembled.

Another object of the present invention is the arrangement of a slotted plunger rod centrally of the rear portion of the barrel and guided for movement centrally of the barrel into and out of engagement with the trigger.

A further object is the provision of simple and effective means for moving the plunger rod rearwardly, comprising a pivoted breakdown lever connected by intermediate links to a pin arranged to float in the slot of the plunger rod, the pin serving to move the plunger rod rearwardly when desired, and then advancing within the slot after engagement of the plunger rod and trigger has been effected.

A further object of this invention is the provision of a breech block member having out-turned lugs at its rear extremity to centralize that portion of the breech block within the barrel and provided at its forward extremity with lugs fitting in recesses in a slotted washer secured within the barrel to centralize such portion of the breech block, whereby the trigger may be readily mounted on the breech block in a central position within the barrel, and the parts co-operating therewith readily maintained in correct positions for insuring engagement of the plunger rod and trigger whenever desired.

The above and other objects and advantages will be apparent from the following description, wherein reference is made to the accompanying drawings illustrating a preferred embodiment of my invention, and wherein similar reference numerals designate similar parts throughout the several views.

In the drawings:

Figure 1 is a side elevation of my improved air rifle.

Figure 2 is a central longitudinal section through the metallic portions thereof show-

ing the interior parts in the positions assumed after a projectile has been expelled.

Figure 3 is a front elevation thereof.

Figures 4, 5, 6 and 7 are detail cross sections taken respectively on the lines 4—4, 55 5—5, 6—6 and 7—7 of Figure 2.

Figure 8 is a view similar to Figure 2 but showing the positions assumed by the plunger rod and co-operating mechanism when moved rearwardly into engagement with the 60 trigger.

Figure 9 is a detail perspective view of the interior portions of the air rifle and plunger rod actuating mechanism removed from the barrel.

Figure 10 is a detail horizontal section taken substantially on the line 10—10 of Figure 2, and

Fig. 11 is a detail perspective view showing the formation of the rear extremity 70 of the plunger rod.

Referring now to the drawings, the numeral 12 designates the stock of the gun, 13 the barrel, and 14 an interior projectile barrel arranged substantially centrally of the 75 forward portion of the barrel 13. The barrel 13 carries the usual front sight 15 and rear sight 16, and, as best illustrated in Figures 2 and 3, the front sight is preferably formed integrally with a centrally apertured 80 end closure member 17 filling the front end of the barrel 13 and being held in position by means of radial lugs 17^a fitting into notches in the barrel 13. The forward extremity of the inner projectile barrel 14 passes through 85 the central aperture of the closure member 17 and is then flared outwardly to prevent separation of the projectile barrel from the closure member. The projectile barrel 14 also preferably has a slight taper from its forward toward its rear extremity to facilitate the entrance and exit of projectiles, the rear extremity of the barrel 14 having an inner diameter slightly less than that of the projectile designed to be used therein. The rear 95

extremity of the projectile barrel 14 is maintained substantially centrally of the outer barrel 13 by means of a washer 18, preferably welded or otherwise secured to the barrel 14. (Note Figure 2.) Rearwardly of the washer 100

18 is arranged one or more centrally apertured packing members 19, of leather or the like, the central apertures of the packing members preferably fitting snugly over the rear extremity of the projectile barrel 14 beyond the washer 18. The projectile barrel 14 extends through a sleeve member 20, reinforcing the outer barrel 18, the arrangement being such that the outer portions of the washer 18 and packing 19 are also backed by the sleeve 20 whereby air compressed by the plunger 23 may not escape around the exterior of the packing members 19. The outer barrel 13 may be made from one sheet of metal, or, as herein shown, the rear portion thereof may be formed from one sheet of metal and the forward portion thereof of tubing, and the sleeve 20 utilized for securing adjacent extremities of the two portions in abutting relation, substantially as shown in Figure 2.

Rearwardly of the sleeve 20 is arranged the plunger rod 21, herein shown as formed from sheet metal reinforced at its rear extremity by bending a portion of the metal back upon the adjacent portion to give double thickness where the contact of the plunger rod with the trigger is secured, as best shown in Figures 10 and 11. A notch 21^a is formed in the lower portion of the plunger rod adjacent the thickened rear extremity thereof and the rear wall of such notched portion is contacted by the trigger 22 when the air rifle is cocked. The forward extremity of the plunger rod carries the usual plunger 23, snugly fitting within the outer barrel 13, and intermediate its ends the plunger rod 21 is provided with an elongated slot 24 in which moves the central portion of the floating pin 25, the ends of which pin pass through openings in the forward extremities of a pair of links 26 arranged on opposite sides of the plunger rod. The rear extremities of the links 26 are pivotally connected to the forward extremity of the lever 27, which is pivoted intermediate its ends, as by the bolt 28, upon a lower extension 29 of the barrel 13. (Note Figures 1 and 2.) By virtue of this arrangement swinging of the lever 27 from its normal position as shown in Figure 2 to the full line position shown in Figure 8 will bring the floating pin 25 into engagement with the rear wall of the slot 24 and then slide the plunger rod rearwardly until its notched portion 21^a contacts the sear 22^a of the trigger 22. Return movement of the lever 27 will then advance the floating pin and links 26 relatively to the plunger rod, the pin 25 merely sliding within the elongated slot 24. Such rearward movement of the plunger rod 21 is utilized to compress a comparatively heavy power spring 30 surrounding the forward portion of the plunger rod between the plunger 23 and a slotted washer 31 arranged at the forward extremity of the breech block 32. A light spring 33 arranged between the stock 12 and

the trigger 22 maintains the trigger in substantially the position shown in Figure 2 so that the sear 22^a thereof is always in position to be contacted by the notched portion 21^a of the plunger rod. When the trigger is pulled, the sear 22^a thereof is swung downwardly out of engagement with the notched portion of the plunger rod, whereupon the compressed power spring 30 will throw the plunger rod forward with great force, and a projectile lodged within the inner barrel 14 will be forcibly expelled in the usual manner of air rifles.

Within the rear portion of the barrel 13 is arranged my improved breech block 32, and the arrangement is such that economy of manufacture and assembling is combined with means for insuring the maintenance of the plunger rod and co-operating parts in the desired positions substantially centrally of the barrel 13. As best shown in Figures 7 and 9 the body of the breech block 32 is formed of sheet metal in a substantially inverted U-shape and provided with laterally extending flanges 32^a of requisite size and shape to snugly fit within the rear portion of the barrel 13 and thereby hold the main portion of the breech block 32 centrally of the barrel. The forward extremity of the breech block 32 is formed with a pair of forwardly extending lugs 32^b (note Figures 4 and 10), fitting within notches in the washer 31, which notches are arranged at opposite sides of the central polygonal aperture of such washer and well inwardly of the periphery to thereby centralize the forward extremity of the breech block 32 within the barrel 13. The forwardly extending lugs 32^b extending within the notches in the washer 31 also permit the washer 31 to be solidly secured to the breech block and backed by the body portion of the breech block to resist any tendency toward displacement during the movements of the power spring 30. The trigger 22 is pivotally mounted upon a bolt 22^b passing through both sides of the barrel 13 and the spaced sides of the body portion of the breech block 32, the trigger being arranged between the side portions of the breech block and thereby maintained in substantially central position for engagement by the plunger rod 21 whenever desired. The stock 12 is secured to the metallic portions of the gun by means of the cross bolt 33' and the top screw 34.

The body portion of the breech block 32 is provided with a pair of elongated slots 32^c arranged one in each side and at the proper height to align with the elongated slot 24 in the plunger rod. The slots 32^c provide guides for the pin 25 during the movements thereof whenever the lever 27 is rocked to bring the plunger rod into engagement with the trigger and during the return of the lever to its normal position. The

pin 25 extends through the aligned slots 24 and 32^c and into apertures in the links 26 and such arrangement aids in maintaining the links in raised position out of contact with the lower portion of the barrel 13. It is to be noted that the links 26 are positioned between the sides of the barrel 13 and the sides of the body portion of the breech block 32, whereby the moving plunger rod and links 10 are maintained out of contact with each other by the intervening guide walls and possible friction is prevented. The polygonal slot in the washer 31 also serves to aid in maintaining the plunger rod centrally within the 15 barrel and out of contact with the body portion of the breech block.

The lever 27 is preferably formed from sheet metal into substantially the shape shown, the spaced side walls thereof serving to strengthen the piece while providing a wide bearing on the fulcrum bolt 28 and completely filling the gap between the spaced sides of the barrel extension 29. The lever is further shaped to form the usual trigger 25 guard, and in addition furnishes a simple and highly effective means for latching the lever upon the barrel 13 whenever the lever is in its normal position. This latching arrangement is best shown in Figures 1 and 7, 30 the elongated side portions 27^a of the lever being bowed outwardly at their free extremities and co-operating with the flared and bowed lower extremities of the extension 35 on the barrel 13. The flare of such extensions 35 guides the side portions 27^a of the lever into the space between the sides of the barrel, and since the thickness of the material of which the barrel is formed is much greater than that of the lever, the extensions 35 40 form stiff posts which serve to flex the bowed side portions 27^a of the lever inwardly until they ride over the correspondingly bowed portions of the extensions, after which the resiliency of the side portions 27^a returns 45 the bowed extremities thereof outwardly into latching engagement with the bowed portions of the extensions 35. The comparatively long side portions 27^a permit ready flexing well within the elastic limit of the 50 material with consequent longevity and ease of operation.

From the above it will be apparent that my improved air rifle is constructed of comparatively few parts, which may be readily manufactured and quickly assembled or disassembled. To remove the motivating parts of the rifle from the fixed portions thereof it is only necessary to remove the three cross bolts 22^b, 28 and 33, and the top screw 34. The stock 12 may then be pulled rearwardly from the metallic portions of the rifle, the trigger 22 permitted to fall from the breech block, and the entire assembly of breech block, power spring, plunger rod, and plunger rod actuating mechanism removed as a

unit from the barrel portions, by grasping the exposed portions of each unit and pulling them rearwardly from the barrel portions of the rifle. Such interior unit is shown in Figure 9. This unit may be readily assembled preliminarily to the assembling of the complete rifle, as may be the barrel portion of the rifle with its inner projectile barrel 14 and sights. The complete assembly of the rifle may then be quickly secured by thrusting the inner unit into the barrel, inserting the trigger, and screwing home the bolts 22^b, 28 and 33, one side of the barrel being preferably tapped to receive the threads of these bolts. The top screw 34 is then secured to prevent any movement of the stock 12 relatively to the remainder of the gun.

The strengthening of the rear extremity of the plunger rod by doubling the thickness thereof aids materially in lengthening the life of the air rifle, and also insures firm contact of the plunger rod with the trigger, even though the trigger may move laterally upon its bolt 22^b. Such lateral movement of the trigger, however, is effectively prevented in my improved rifle by the centralized arrangement of the body portion of the breech block within the barrel.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

Having described my invention, what I claim is:

1. In a gun, a barrel, a plunger having a slotted plunger rod slidable therein, a power spring surrounding the plunger rod, a trigger, and means for sliding the plunger rod rearwardly against the tension of said spring into engagement with the trigger, the portion of the plunger rod contacting the trigger being bent back upon itself to form a portion of greater thickness than the remainder thereof.

2. In a gun, a barrel, a plunger having a slotted plunger rod slidable therein, a power spring surrounding the plunger rod, a trigger, and means for sliding the plunger rod rearwardly against the tension of said spring into engagement with the trigger, the plunger rod being formed of sheet metal with the rear portion thereof folded back on the adjacent portion to thicken and reinforce the rod where it contacts the trigger.

3. In a gun, a barrel, a plunger having a slotted plunger rod slidable therein, a power spring surrounding the plunger rod, a trigger, means for sliding the plunger rod rearwardly against the tension of said spring into engagement with the trigger, and means for centralizing the trigger and plunger rod

including a removable breech block member arranged within the rear portion of the barrel and having guide walls and projecting portions to space the same from the sides of the barrel.

4. In a gun, a barrel, a plunger having a slotted plunger rod slideable therein, a power spring surrounding the plunger rod, a trigger, means for sliding the plunger rod rearwardly against the tension of said spring into engagement with the trigger, means for centralizing the trigger and plunger rod including a removable breech block member arranged within the rear portion of the barrel and having guide walls spaced from the sides of the barrel by outturned flanges adjacent the rear extremity of the breech block member, and a slotted washer encircling the plunger rod and having recesses receiving the forward extremities of the breech block member.

5. In a gun, a barrel, a plunger having a plunger rod slidable therein, a power spring surrounding the plunger rod, a breech block member secured within the rear portion of the barrel having guide walls and integral projecting portions to maintain the same centrally within the barrel, the rear portion of the plunger rod extending between said guide walls, a trigger pivotally mounted between the guide walls of the breech block member, and means for sliding the plunger rod rearwardly against the tension of said spring into engagement with the trigger.

5 6. In a gun, a barrel, a plunger having a slotted plunger rod slidable therein, a power spring surrounding the plunger rod, a breech block member secured within the rear portion of the barrel and having guide walls centrally

40 arranged within the barrel, the rear portion of the plunger rod extending between said guide walls, a trigger pivotally mounted between the guide walls of the breech block member, means for sliding the plunger rod

45 rearwardly against the tension of said spring into engagement with the trigger, said means including a pin floating in the slot of the plunger rod, a pair of links arranged exteriorly of the guide walls of the breech block
50 member and pivoted on said pin, and a lever fulcrumed upon the barrel and pivotally connected to said links.

7. In a gun, a barrel, a plunger having a slotted plunger rod slidable therein, a power spring surrounding the plunger rod, a breech block member secured within the rear portion of the barrel and having guide walls centrally arranged within the barrel, the rear portion of the plunger rod extending between said guide walls, a trigger pivotally mounted between the guide walls of the breech block member, means for sliding the plunger rod rearwardly against the tension of said spring into engagement with the trigger, said means including a pin floating in the slot of the

plunger rod, a pair of links arranged exteriorly of the guide walls of the breech block member and pivoted on said pin, and a lever fulcrumed upon the barrel having spaced side members respectively pivotally connected with said links exteriorly of said guide walls. 70

8. In an air rifle, a barrel channel-shaped at its rear extremity, and a removable unit for insertion into said barrel from the rear thereof, said unit comprising a plunger having a slotted plunger rod, a breech block member having spaced guide walls provided with integral means for locating the breech block member substantially centrally in and spaced from the side walls of the barrel, a trigger arranged between said guide walls, a power spring surrounding the plunger rod between the plunger and the breech block member, a lever, and links connecting the lever with the slotted portion of the plunger rod. 75 80 85

9. In an air rifle, a barrel channel-shaped at its rear extremity, and a removable unit for insertion into said barrel from the rear thereof, said unit comprising a breech block member having spaced guide walls provided with forwardly extending lugs, means for centrally locating the rear portion of the breech block member within the barrel, a slotted washer having recesses for receiving said lugs of the breech block member, a trigger adapted to be pivoted between said guide walls, a plunger having a slotted plunger rod extending through said slotted washer into the space between said guide walls, a power spring surrounding the plunger rod between the plunger and said washer, and means for sliding the plunger rod rearwardly against the tension of said spring into engagement with said trigger. 90 95 100 105 110 115 120 125 130 135 140 145 150 155 160 165 170 175 180 185 190 195 198 199 200

10. In a gun, a barrel, a plunger having a slotted plunger rod slideable therein, a power spring surrounding the plunger rod, a breech block member secured within the rear portion of the barrel and having slotted guide walls arranged within the barrel, the rear portion of the plunger rod extending between said guide walls, a trigger pivotally mounted between the guide walls of the breech block member, means for sliding the plunger rod rearwardly against the tension of said spring into engagement with the trigger, said means including a pin floating in the slot of the plunger rod and the slots in the guide walls of the breech block member, a pair of links arranged exteriorly of said guide walls and pivotally connected to said pin, and a lever fulcrumed upon the barrel and pivotally connected to said links.

11. In a gun, a barrel, a plunger having a 125
slotted plunger rod slidable therein, a power
spring surrounding the plunger rod, a trig-
ger, means for sliding the plunger rod rear-
wardly against the tension of said spring into
engagement with the trigger, said means in- 130

cluding a pin floating in the slot of the plunger rod, a pair of links pivoted on said pin on each side of the plunger rod, a lever also pivotally connected with the links, said lever including a pair of spaced resilient latching elements, and co-operating latch elements carried by the barrel for normally engaging the latching elements of the lever to maintain the lever in juxtaposition to the barrel.

12. In a gun, a barrel, a plunger having a slotted plunger rod slidable therein, a power spring surrounding the plunger rod, a trigger, means for sliding the plunger rod rearwardly against the tension of said spring into engagement with the trigger, said means including a pin floating in the slot of the plunger rod, a pair of links pivoted on said pin on each side of the plunger rod, a lever 15 also pivotally connected with the links, said lever being fulcrumed adjacent its forward extremity on the barrel and being formed rearwardly of its fulcrum with a resilient latching element having its free extremity bowed and a flared and bowed latching portion carried by the barrel for co-operation with the latching element of the lever to normally maintain the lever in juxtaposition to the barrel.
